UNITED STATES PATENT OFFICE.

ELMER E. FREDERICK, OF EASTON, PENNSYLVANIA.

TROLLEY.

SPECIFICATION forming part of Letters Patent No. 739,164, dated September 15, 1903.

Application filed April 30, 1903. Serial No. 155,045. (No model.)

To all whom it may concern:

Be it known that I, ELMER E. FREDERICK, a citizen of the United States, residing at Easton, in the county of Northampton and State of Pennsylvania, have invented a new and useful Trolley, of which the following is a specification.

This invention relates to electric-current collectors, but more particularly to overhead trolleys.

One of the objects of the invention is to provide an efficient trolley which maintains a perfect contact with the trolley-wire and at the same time avoids friction therewith, whereby the liability of the current being interrupted, so as to spark the motor in the car, will be reduced to a minimum.

A further object is to construct a current-collector which will not be subject to deterioration by the atmospheric changes, so as to reduce the efficiency thereof.

Further objects and advantages of this invention will appear in the following description, and the novel features thereof will be particularly pointed out in the appended claims, it being understood that various changes in the form, proportion, and minor details of construction may be resorted to without departing from the spirit or sacrificing any of the advantages of this invention.

In the drawings, Figure 1 is a vertical longitudinal sectional view of a trolley constructed in accordance with my invention, and Fig. 2 is a vertical sectional view on the line 22 of Fig. 1.

In the preferred embodiment of my invention, as illustrated in the accompanying drawings, the collector is shown as a trolley-harp 1, having the usual forked or bifurcated end 2, which carries the contacts for the trolley-wire 3, lying in the intersecting space 4, formed by the arms 5 and 6 of the harp. The contacts carried by the harp each consists of a spherical body 7 within a cup 8, provided with a circular groove or raceway 9, in which antifriction-balls 10 are disposed, so as to permit the spherical body 7 to turn in all directions. These balls can be held in the raceway by ball-retainers 11, if desired. The cups 8 are of the same interior diameter, though

both ends are threaded exteriorly, being provided with angular openings 12 for the insertion of a tool to apply or remove them. In actual practice the cups will be secured in the arms 5 and 6 and at the base of the intersecting space 4. It will be seen that the contacts are arranged in pyramidal formation in aggroupment, so that the oppositely-disposed edges of the cups carried by the arms 5 and 6 will slightly overlap the edges of the lower cup and prevent any displacement of the spherical body 7 therefrom. Either or both of the upper cups can be adjusted in the arms 5 and 6 to decrease or increase the distance from one to the other, and thus limit the upward movement of said lower spherical body, as well as prevent the displacement of the bodies which they carry. It will also be observed that the cups and the spherical contacts carried thereby are interchangeable, owing to the fact that they are structural equivalents. When it is necessary to replace or repair one of the contacts, a new one can readily be substituted from a stock supply, thus resulting in a considerable saving in time and expense.

By utilizing such a construction of collector as described by me a perfect and even contact with the trolley-wire will be assured at all times, and the usefulness of the motor will be greatly prolonged, owing to the absence of sparking due to imperfect contacts. As each of the spherical bodies 7 is capable of moving in all directions and as the upper contacts are slightly spaced apart from the lower one, a groove is formed into which the trolley will have a tendency to lie, and thereby prevent jumping of the trolley from the wire.

What I claim is—

1. A current-collector having an aggroupment of removable contact-retaining receptacles, one of which is a retaining element for another.
2. A current-collector having an aggroupment of independently-adjustable contact-containing receptacles one of which is a retaining element for another.
3. An electric-current collector comprising a carrier having a plurality of receptacles

with movable bodies therein, the movable body in one of the receptacles being retained by the other receptacles.

4. An electric-current collector comprising a carrier having a plurality of receptacles arranged in pyramidal formation so that the edges of one of the receptacles are overlapped by the edges of the adjacent receptacles, and a movable body held in the receptacle by the overlapped edges.

5. An electric-current collector comprising

a carrier having an interposed contact and side contacts adjustable toward and away from each other.

In testimony that I claim the foregoing as my own I have hereto affixed my signature in the presence of two witnesses.

ELMER E. FREDERICK.
